TABLE

Arnold P. Ginsburg, Los Angeles, Calif.
(1794 Kelton Ave., West Los Angeles, Calif. 90025)

Filed Mar. 1, 1972, Ser. No. 231,064

Term of patent 3½ years

Int. Cl. D6—03

U.S. Cl. D6—179

FIG. 1 is a perspective view of a table showing my new design.

FIG. 2 is a front elevational view of the right hand part of the table showing the details thereof.

FIG. 3 is a side elevational view of the table.

I claim:

The ornamental design for a table, as shown.
